UNITED STATES PATENT OFFICE.

JOHN J. CHAPIN, OF DETROIT, MICHIGAN, ASSIGNOR TO BURROUGHS ADDING MACHINE COMPANY, OF DETROIT, MICHIGAN, A CORPORATION OF MICHIGAN.

TYPE-WRITING MACHINE.

1,169,770.

Specification of Letters Patent.

Patented Feb. 1, 1916.

Application filed September 2, 1908. Serial No. 451,361.

To all whom it may concern:

Be it known that I, JOHN J. CHAPIN, a citizen of the United States, residing at Detroit, in the county of Wayne and State 5 of Michigan, have invented certain new and useful Improvements in Type-Writing Machines, of which the following is a specification.

The present invention relates to improvements having more especially to do with the type bar action, one object being to provide for increased lightness of touch on the keys by a novel arrangement of retracting spring for the type bars, which arrangement at the same time provides for increased speed of operation in causing a quickened recovery of the type bars.

A further object is to so construct and arrange the operating connections between the 20 character key levers and the type bars as to provide for a slow and easy start with acceleration as the type approach the platen and the highest rate of speed when the limit of movement of the key levers is reached.

Furthermore the arrangement of these connections is such as to eliminate cramping on any of the pivots, stress in any unit of such connections being in the direction of the radiating plane of such unit. In these operating connections pull wires or links which transmit movement to the pivoted type bars are so arranged that any such pull wire or link will in operation be carried away bodily from neighboring pull wires or links thereby 35 eliminating collision of pull wires and permitting a greater extent of the arc of the type bar supporting segment to be employed than heretofore and thus allowing for increased spacing apart of the type bars.

A further object of the invention is to provide an improved construction for supporting pivotal parts such as the type bars and their operating bell cranks, which construction will provide for distribution of 45 wear and consequently for prolonging the life of the machine as well as preserving the alignment in typewriting.

The invention also provides improvements in the upper and lower case mountings and 50 controlling devices, calculated to secure easy and uniform action and simple and effective adjustments suited to the particular work in hand.

With these and incidental objects in view 55 the invention consists in certain novel fea-

tures of construction and combinations of parts, the essential elements whereof are recited in the appended claims and a preferred form of embodiment of which is described in detail hereinafter and fully illustrated 60 in the accompanying drawings forming a part of this specification.

Of said drawings Figure 1 represents a general vertical section of a typewriting machine taken from front to rear, various features of the present invention appearing; Fig. 2 represents the type centering guide detached in perspective; Fig. 3 represents a partial vertical cross section on an enlarged scale with some parts appearing in front 70 elevation; Fig. 4 represents a top plan view of the machine with a number of parts omitted; Fig. 5 is a detail sectional view showing one of the bell crank levers of the type bar operating connections and its pivotal mounting; Fig. 6 is a fragmentary front elevation of the same with others of the bell cranks; Fig. 7 is a sectional elevation on an enlarged scale as compared with Fig. 1, illustrating a type bar action or unit; Fig. 8 is a fragmentary rear elevation of the type 75 bar segment with type bars mounted therein and retracting spring applied; Fig. 9 is a detail sectional view on the line 9-9 of Fig. 7; Fig. 10 is a cross section on an enlarged 80 scale of the type bar pad; Fig. 11 is a sectional elevation of upper case shift key and connections; Fig. 12 is a somewhat similar view illustrating a different adjustment; and Fig. 13 is a fragmentary front elevation 85 of parts shown in Figs. 11 and 12.

In the drawings the reference numeral 2 designates the supporting frame-work of the machine, 3 the laterally movable paper carriage, 4 the roller platen carried thereby, 5 character key levers extending horizontally in the lower portion of the frame-work and fulcrumed at their rear ends on an overhanging portion of the frame-work, being normally upheld by spiral springs 6; 95 and 7 type bars pivoted in a segmental plate 8 and adapted to swing up and rearward against the platen 4. The segmental plate 8 is radially slotted in its lower edge a sufficient depth to provide for a full 105 swing of the type bars, the latter occupying the slots respectively so as to strike at a common point on the front of the platen. Each type bar is formed at its pivot end with a slight protuberance providing a 110

radial shoulder 9 normally lying within the slot of the segment near the front side of the latter as shown in Fig. 7 but adapted when the type bar swings to the limit of its movement to project beyond the rear side of the segment as shown by dotted lines in said figure. On the back of the segment there is secured a steel plate 10 (Figs. 7 and 8) formed with a series of resilient fingers 11 whose end edges normally lie closely adjacent terminal concentric edges of the type bars, one finger in the present instance embracing two type bars, though this arrangement may of course be varied. 10 As a type bar approaches the end of its upward and rearward swing its shoulder 9 encounters the finger 11 which yields, permitting the type to be thrown forcibly against the platen. This can and in practice does 15 come about through the impetus of the moving parts under actuation by finger pressure on a character key, so that the spring finger instantly recovers, throwing the type bar back away from the platen without 20 waiting on release of finger pressure. It will be seen that with this construction the spring offers no resistance whatever during the touch on the key and only comes into play to cause quick recovery of the type bar 25 from the actual impression advance produced by reason of gathered impetus during actuation under finger pressure. At the same time the arrangement provides for instantly starting the type bar on its return 30 movement so that not only is extreme lightness of touch preserved but high speed in 35 operation provided for.

The type bars of course lie in radiating planes and it is desirable to so arrange operating connections between them and the horizontal character key levers so as to reduce to the minimum any tendency toward cramping on pivots, the keyboard necessarily occupying considerably more lateral 40 area than the types. Bell cranks are employed intermediate the key levers and the type bars, the same being preferably supported by a curved bar 12 extending between the sides of the framework and secured thereto. This bar extends on an arc of a radius somewhat greater than that of the segment 8 and is located forward of the latter and in a lower plane. The bell cranks extend in convergent planes not 45 radial to such arc or that of the segment but providing for straight lines of connection between the bell cranks and the key levers 5. Forwardly projecting arms 13 of the bell cranks lie normally horizontal, these 50 arms having coupled to their forward ends pull wires or links 14 which extend to the key levers respectively and are pivotally connected therewith, said pull wires or links lying in the respective planes of the bell 55 cranks as clearly shown in Fig. 3. The

other arms 15 of the bell cranks extend upward at an obtuse angle to the arms 13 thus normally inclining rearward. To the upper extremities of these bell crank arms 15 pull wires or links 16 are pivotally connected, 70 the rear ends of these links or pull wires being pivotally connected to projections 17 of the type bars respectively, such projections in the normal position of the type bars extending downward and rearward from 75 the pivots of the bars as illustrated in Fig. 7. These pull wires or links lie in cylindrical series with rear ends normally slightly above horizontal lines embracing the front ends. Under upper case shift the rear ends 80 of said pull wires or links are slightly below such horizontal lines the same distance as they are normally above such lines. It will be seen that the arrangement of connections as above described is calculated to 85 reduce to the minimum any cramping on the pivots, the pull wires receiving the initial stress of finger pressure in line with the bell crank levers which transmit movement to the type bars. Furthermore the 90 normal disposition of the arms 13 of the bell cranks provides for the maximum leverage in application of finger pressure power whereas the disposition of the arms 95 15 of said bell crank levers provides for an increasing leverage in transmission of such power to operate the type bars. Thus the action can be started easily under a light touch and accelerated as the type bar approaches the printing position. It should 1 be noted that both ends of pull wires or links 16 rise in actuation of type bars, the extremities of the bell crank arms 15 swinging upward inasmuch as they normally incline rearward, and the extremities of 1 the type bar projections 17, after a very slight downward swing, also swinging upward and forward. It results that pressure on a character key carries the connected link or pull wire 16 bodily forward and upward 11 away from the rest of the pull wires or links. Consequently the parts are not required to be assembled with regard to possible collision of such pull wires as when one end drops and the other rises, hence there is 12 no limitation on this account to the segmental extent of the series of type bars and connections. It follows that more of the supporting segment 8 can be utilized and the type spaced farther apart.

The pivotal mounting of both type bars and bell cranks is such as to provide for distribution of wear and therefore preservation of alignment in the typewriting. As the construction for each of these sets of 13 pivotal parts is practically identical a description of one will suffice for both. The bell cranks 13-15 occupy cross slots in the bar 12 (Figs. 5 and 6) such slots of course 14 converging or radiating in the same planes 15

as the bell cranks. The bar is also slotted longitudinally and recessed at the base of this longitudinal slot or groove as shown at 18 to accommodate a pivot rod or wire 19 which extends through pivot holes in the several bell cranks, said pivot holes being regulated in size according to angularity of the bell cranks relative to said pivot rod. The ends of this pivot rod or wire are screw-threaded and project above the bar 12 receiving adjusting nuts 20 on their ends, which nuts seat against prepared angular surfaces of the bar. By the use of these nuts which are suitably knurled for manipulation, the pivot rod or wire can be shifted longitudinally so as to vary the points of bearing of the bell cranks thereon and distribute the wear throughout the length of the rod. It will be obvious that this construction provides a ready means for prolonging the life of the machine while preserving the alignment.

The springs 6 heretofore mentioned as normally upholding the character key levers 25 are seated in sockets of a cross bar 21 (Figs. 7 and 9) extending between the sides of the supporting framework and adjusting screws 22 are entered through the underside of this cross bar, said screws being slotted at both ends and the lower extremities of the springs being engaged with the upper slots. The upper ends of the springs abut against the sides of the levers 5. By turning any one of the screws 22 by application of a screw-driver to its outer slot the tension of the spring 6 can be increased, the upper end of the spring being forced past the under-edge of the key lever and the extremity of the spring snapping past such lever and serving to prevent unwinding of the spring by abutment against the side of the lever and the screw being correspondingly locked against backward turning.

There is secured to the front of the segment 8 at a central position a type centering guide. This comprises a substantial piece of steel with a base or body portion 23 screwed to the segment, upright side arms or tines 24 and central fingers or tines 25 spaced from said arms 24 and from each other but tending to spring toward the arms respectively and away from each other, said fingers being reduced at their bases to increase resiliency. The upper ends of the fingers 25 have forwardly-projecting portions 26 whose confronting edges converge to the slit between the fingers, the latter being also slightly rounded out in flaring formation below such forwardly-projecting portion. The type bar heads just below the type bearing portions strike between the upper ends of the fingers 25 where the arms 24 are located and the construction above described provides for the proper centering of the type. Screws 27 are entered through

threaded openings in the upper ends of the arms 24 to bear against the outer sides of the fingers 25 respectively and said screws have lock nuts 28 applied to them. By means of these screws and lock nuts the centering fingers can be exactly adjusted. It has been stated that these fingers tend to spring away from each other, therefore it will be obvious that by turning back one of the screws 27 and screwing up the other the guide can be firmly and accurately adjusted.

The basket in which the type bars normally rest comprises suitable horizontal supporting rods 30 projecting from the segment 8, a curved bar 31 secured thereto edge up and formed with a series of forwardly-projecting fingers 32, and a curved plate 33 supported by and secured to said fingers. A comparatively thick strip of felt or like material 34 is laid upon this plate 33 and on this felt strip rests a pad comprising an outer sheath 35 of pliable material such as linen or other textile stuff but preferably a piece of kid. This sheath constitutes a bag or sack for layers 36 of soft metal preferably tin foil, which layers may be formed by taking a sheet of tin foil and folding it back and forth as shown in Fig. 10. The type bar heads come to rest against this pad which with the interposed felt strip is suitably secured to the plate 33 as by rivets 37. The construction of the pad as above described provides for the type heads falling against the same with a deadening effect practically eliminating rebound. It will be obvious that the layers of soft metal such as tin foil are calculated to produce the desired deadening effect and at the same time there is no tendency to so far harden or change shape in use as to disturb the arrangement or performance of the type bars.

Passing now to the upper and lower case shift, the segment 8 is formed at opposite sides with projecting arms 40 and there is journaled in bearings at opposite sides of the framework a rock shaft 41 at a point in rear of the segment, said shaft carrying forwardly-projecting arms 42 just inside the framework and bored to pivotally support the segment arms 40. A leg 43 is secured to and depends from the central portion of the segment 8 on the rear side thereof as shown in Figs. 1, 4 and 7 and this leg has jointed to its lower end a link 44 which extends rearwardly and is pivotally mounted in an upright 45 rising from the rear lower cross piece of the supporting framework. The forward end of this link is normally slightly above the horizontal but when the segment 8 is lowered for upper case work the forward end of said link is the same distance below the horizontal. The same thing is true of the arms 42 and as the distance between the point of pivotal connection of the link 44 and leg 43 and a horizontal plane

embracing the points of pivotal connection between the arms 42 and the segment, is normally the same as the distance between the rear pivot of said link and the horizontal plane embracing the axis of the shaft 41, the segment 8 and parts carried thereby when fully shifted will occupy the same planes as before.

It is to be noted that the segment moves 10 in a vertical direction whereas the arms 42 and 44 which guide the same and the links 16 by which the type bars are operated from the bell crank levers all lie in substantially horizontal planes. As a result of this construction the shifting of the segment has no effect upon the key levers, bell cranks or the links which connect these levers for the reason that the slide movement of the segment or basket in a flat arc substantially normal 15 to the links 16 does not materially alter the distance between the pivotal connections of the latter to the type bars and key levers respectively. By this arrangement unnecessary rattling of the keys is prevented. 20 The extent of movement of the segment is controlled by means of set screws 46 entered through flanges of the framework and carrying lock nuts 47, there being a pair of said set screws at each side of the machine and 25 each arm 42 being formed with a depending portion carrying a laterally projecting stud or pin 48 which projects between said set screws.

The means for effecting the shift of the 30 segment comprise arms 49 projecting rearwardly from the shaft 41 and connected by springs 50 to the frame-work of the machine, said springs thus holding the segment up and operating to restore it to the upper position after having been lowered. Shift keys 51 and 52 are carried on the forwardly-extending substantially horizontal arms 53 and 54 of a pair of bell crank levers pivoted at their angles upon frame studs 55. Up-standing arms 56 and 57 of these bell 40 crank levers lie in rear of and are adapted to act upon depending arms 58 and 59 of bell cranks respectively, the latter pivoted on opposite sides of the framework and having rearwardly-extending arms 60 and 61 bifurcated at their rear ends to embrace the segment arms 40 respectively where their pivot portions protrude through the arms 42. It will be obvious that depression of 45 either key 51 or 52 through connections above described will result in depression of the type bar segment. In order to keep the bell crank key levers in line with the segment operating bell cranks, the arms 56 and 57 of the former carry U-shaped pieces 63 embracing the depending arms 58 and 59 of the operating bell cranks.

Either of the keys 51 or 52 may operate simply to temporarily hold the segment

down as when printing a single upper case 60 character or the right-hand key 51 may be employed to lower the segment and cause it to be held down indefinitely, the other key 52 then operating to release the segment. Thus there is pivoted in a front portion of 65 the framework a small lever 70 with a knob 71 on its outer end and a lateral pin or stud 72 on its inner end, the lever being pivoted intermediate its ends. A spring 73 connects the stud 72 with a fixed stud on the machine 70 frame, such spring thus tending to elevate the rear end of the lever and lower its forward end. When free to do so this spring holds the stud 72 normally against the lower end of the bell crank arm 59 as shown in 75 dotted lines in Fig. 11. Under such conditions when the right-hand shift key 51 is depressed and said bell crank arm 59 thus swung forward the pin or stud 72 will spring up behind said arm as shown in Fig. 80 12, latching the segment down without back lash. Rearwardly beyond this stud or pin the lever 70 has a cam edge 74 adapted for co-action with a pin or stud 75 on the arm 57 of the left-hand shift key lever. Thus 85 when, after use of the right-hand shift key lever to permanently lower the key bar segment, it is desired to release the same it is merely necessary to depress the left-hand shift key thus causing the pin or stud 75 to 90 cam down the rear end of the lever 70 freeing the bell crank arm 59 from the restraint imposed upon it by the pin or stud 72. Of course even when the lever 70 is in the dotted line position shown in Fig. 11 depression of the shift key 52 will not result in leaving the key bar segment lowered because the pin or stud 75 will prevent the lever from moving up to latching position. Said lever 70 may be adjusted to inactive 95 position altogether when it is desired to use either shift key for simply a temporary upper case shift. A spring friction catch piece 76 is fastened to the framework just inside the slotted portion thereof through which the lever 70 projects, such catch piece being shouldered as at 77 (Fig. 13) so that when the front end of said lever is raised to the position shown in full lines in Fig. 11 it will be so held against the stress of the spring 73 which is incapable of overcoming the friction between the lever and the shoulder thereof. Such friction can be readily overcome by finger pressure when it is desired to have the lever in active position.

It will be obvious that, when the segment and basket have been lowered and latched by use of the righthand shift key 51, the release can be effected as well by lifting the knob 71 as by the previously mentioned depression of the left-hand shift key 52.

While the above described constructions are well adapted to fulfil the objects pri-

marily stated yet it is to be understood that these constructions are susceptible of modification within the scope of the invention.

What I claim is:

5. 1. In a typewriting machine, the combination with a frame and pivoted type bars, the latter having radial shoulders adjacent their pivots, of a plate secured to the frame and having spring fingers arranged to be 10 encountered by the shoulders on the bars as they reach the point of impact.
2. In a typewriting machine, the combination with pivoted type bars, of a plate having spring fingers arranged to be 15 encountered by the bars as they reach the point of impact, each finger coöperating with a plurality of type bars.
3. In a typewriting machine, the combination of horizontal parallel key levers, a 20 segmental series of bell cranks in radiating planes, radiating links connecting said bell cranks with the key levers respectively, a segmental series of type bars, and links connecting the same with the bell cranks respectively.
4. In a typewriting machine, the combination of horizontal parallel key levers, a 25 segmental series of bell cranks in radiating planes, one arm of each bell crank normally extending horizontally, radiating links connecting said bell cranks with the key levers respectively, a segmental series of type bars, and links connecting the same with the bell cranks respectively.
- 30 5. In a typewriting machine, the combination of horizontal parallel key levers, a segmental series of bell cranks in radiating planes, one arm of each bell crank normally extending horizontally and the other upwardly at an obtuse angle to the horizontally extending arm, radiating links connecting said bell cranks with the key levers respectively, a segmental series of type bars, and links connecting the same with the bell cranks respectively.
- 35 6. In a typewriting machine, the combination of horizontal parallel key levers, a segmental series of bell cranks in radiating planes, one arm of each bell crank normally extending horizontally and the other upwardly at an obtuse angle to the horizontally extending arm, radiating links connecting said bell cranks with the key levers respectively, a segmental series of type bars, 40 and links connecting the same with the bell cranks respectively.
- 50 7. In a typewriting machine, the combination of horizontal parallel key levers, a segmental series of bell cranks in radiating planes, one arm of each bell crank normally extending horizontally and the other upwardly at an obtuse angle to the horizontally extending arm, radiating links connecting said bell cranks with the key levers respectively, a segmental series of type bars, 55 and links connecting the same with the bell cranks respectively, and links connecting the upwardly extending arms of the bell cranks with the type bars respectively below and in rear of the latter's pivots.
- 60 8. In a typewriting machine, the combination of horizontal parallel key levers, a segmental series of bell cranks in radiating planes, radiating links connecting said bell cranks with the key levers respectively, a 65 segmental series of type bars collectively shiftable, and links connecting the same with the bell cranks respectively, the normal position of the last-mentioned links being slightly above the horizontal and their position under shift of the series of type bars 70 being slightly below the horizontal.
9. In a typewriting machine, the combination of a key lever, an adjusting screw, and a spring interposed between the lever and adjusting screw and locked against rotation by its engagement with the lever and engaging the screw in such manner as to be locked against rotation with reference thereto.
10. In a typewriting machine, the combination with a key-lever; of a spiral spring engaging under the same with one end abutting the side of the lever, and a screw holding the other end of the spring by rotative engagement therewith.
11. In a typewriting machine, the combination of a segmental series of type bars, a basket in which the said type bars are pivoted, a rocking member from which the basket is suspended, a radius link applied to the basket, means for yieldingly upholding the basket, means for lowering it, a series of bell cranks, and links connecting the type bars with the bell cranks respectively, the normal position of these links being slightly above the horizontal and their position under shift of the basket being correspondingly below the horizontal.
12. In a typewriting machine, the combination of a type-bar basket or cradle having arms projecting from opposite sides and a central depending leg, a fixed support, a link connecting said leg with the latter, a rock shaft having arms jointed to the side arms of the basket, means for yieldingly upholding the latter, and one or more shift keys and connections for lowering the basket; the distance between the horizontal plane of the rock shaft and the horizontal plane of the connection between said link and the fixed support being the same as the distance normally between the horizontal plane of the point of connection between the link and the central leg of the cradle and the horizontal plane of the points of connection between the rock shaft arms and the arms of the basket.
13. In a typewriting machine, the combination of a type-bar basket or cradle having arms projecting from opposite sides and a central depending leg; a fixed support, a link connecting said leg with the latter, a

rock shaft having arms jointed to the side arms of the basket, means for yieldingly upholding the latter, and one or more shift keys and connections for lowering the basket comprising bell cranks jointed to the side arms of the latter and bell crank key levers engaged with said bell cranks.

14. In a typewriting machine, the combination with a shiftable type bar basket and pivoted arms supporting the same; of shift levers connected therewith; key levers engaging said shift levers; and a latch for engaging one of the latter to hold the basket shifted, said latch adapted to be engaged and displaced by one of the key levers.

15. In a typewriting machine, the combination with a shiftable type bar basket; of shift levers connected therewith; key levers engaging said shift levers; a spring-drawn latch adapted to engage one of the latter to hold the basket shifted, said latch adapted to be displaced by one of the key-levers; and means for holding the latch in inoperative position.

16. In a typewriting machine, the combination with a shiftable type bar basket and pivoted arms supporting the same; of shift levers connected therewith; key levers engaging said shift levers, one having a pro-

jecting stud; and a latch adapted to engage one of the shift levers to hold the basket shifted, and having a cam-edge to coact with the stud of the key lever; substantially as and for the purpose described.

35

17. In a typewriting machine, a vertically movable basket, a rock shaft having forwardly projecting arms engaging and supporting the basket, and a rearwardly extending arm with a spring whereby the basket is normally held elevated, a bell crank lever having a pin and slot connection at one end with an arm on the rock shaft and a key lever connected to the other arm of the bell crank for operating the latter.

45

18. In a typewriting machine, a vertically movable basket, a rock shaft having forwardly projecting arms engaging and supporting the basket, and a rearwardly-extending arm with a spring whereby the basket is normally held elevated, a bell crank lever connected at one end with an arm on the rock shaft and a key lever connected to the other arm of the bell crank for operating the latter.
